UNITED STATES PATENT OFFICE.

MAHLON E. LAYNE, OF HOUSTON, TEXAS.

FIRE-EXTINGUISHING APPARATUS FOR WELLS.

No. 910,295.

Specification of Letters Patent.

Patented Jan. 19, 1909.

Application filed December 3, 1907. Serial No. 404,970.

To all whom it may concern:

Be it known that I, MAHLON E. LAYNE, a citizen of the United States, residing at Houston, in the county of Harris and State of Texas, have invented certain new and useful Improvements in Fire-Extinguishing Apparatus for Wells, of which the following is a specification.

The invention relates to mechanism for placing under control ignited oil gushers. The invention has for its primary objects; the provision of improved mechanism by which the oil flowing from the well may be diverted laterally and the supply of oil and gas diverted from the ignited body of fluid; the provision of a mechanism of the type specified which may be easily and safely placed in position by operators without approaching dangerously near the well, and the provision of mechanism which shall be simple in construction and reliable in operation. Certain embodiments of the invention are illustrated in the accompanying drawings, wherein:

25 Figure 1 is a side elevation of the preferred form of the apparatus.

Figure 2 is an enlarged detail section through the head which fits over the well casing,

30 Figure 3 is an enlarged detail section taken on the line 3—3 of Figure 1,

Figure 4 is a detail section taken on the line 4—4 of Figure 1,

Figure 5 is a detail side elevation of a modified form of construction for anchoring the apparatus to the well casing,

Figure 6 is a transverse section on the line VI—VI of Figure 5, and

Figure 7 is an enlarged sectional detail 40 view on the line VII—VII of Figure 3.

Heretofore it has been found extremely difficult and in many cases impossible to extinguish burning oil and gas wells, because of the pressure of the escaping fluid, and because of the great heat in the immediate vicinity of the well. The apparatus constituting my invention is designed to accomplish the extinguishment of such burning wells, and comprises apparatus 50 for diverting the flow of oil and gas from the mouth of the well laterally through a pipe line whereby the supply of combustible

material to the upper strata of air at which ignition occurs is cut off, and any ignited fluid in the pipe line quenched either because of the insufficient supply of air or by the addition of steam or other vapor. The apparatus is so constructed that the upward flow of fluid from the mouth of the well is unconfined until the device is positioned over the well and securely anchored, at which time the flow of oil is suddenly diverted through the pipe line,

Referring first to the general arrangement of parts as indicated in Figure 1, 1 is the well casing to which it is desired to apply the apparatus, 2 is a laterally extending pipe of sufficient capacity to carry the flow of oil from the well, which pipe has the curved end 3, and is mounted for movement upon two pairs of wheels 4 and 5, 6 is the head of the apparatus which is adapted to be clamped over the top of the well casing 1, 7 is an upward extension through which the oil flows when the apparatus is first placed in position over the well casing 1, and from which the flow is diverted to the pipe 2 after the parts are securely anchored, 8 is a means for operating the valve which diverts the flow of oil from the upright pipe 7 to the pipe 2, which device is operable from the rear part of the apparatus, 9 is a pipe connection to the upright pipe 7, and the lateral pipe 2 through which pipe steam or other extinguishing vapor may be supplied if necessary, and 10 is the pivoted cap secured to the top of the upright pipe 7 and designed to cut off the supply of air to such pipe 7 when the valve in the head 6 has been turned to divert the flow of oil through the pipe 2. The pipe 2 is supported at the wheels 4 by means of the U shaped axle 11 (Fig 3), to which it is secured by means of the brackets 12. Secured on either side of the brackets 12 is the end of the T bar post 13. Secured to the upper end of this post is the truss-rod 14, which truss-rod as shown in Figure 1, is provided with the tightening turn-buckles on either side of the post and is secured at its two ends to the pipe by means of the collars 15. This arrangement is designed to stiffen the pipe 2 which constitutes the back-

bone of the apparatus, and prevent sagging when the wheels 4 are withdrawn from the ground in a manner to be hereinafter described. The construction of the head of the device 6 which is to be secured to the well casing 1 is illustrated in Figure 2. As here shown this head comprises a box portion to which is connected the pipe 7 and the curved end 3 of the pipe 2 in the manner shown: The lower portion 16 of the box 6 is of sufficient size to fit snugly over the end of the well casing 1, and such end is provided with the spring catches 17 which slip over the flange 18 of the well casing 1 and securely lock the head 6 against vertical movement. A converging portion 18' is provided just above the portion 16, which converging portion is designed to prevent the upwardly directed fluid from striking any projecting portions in the box or head 6. In order to direct the fluid from the pipe 7 to the end 3, the swinging valve 19 is provided, which valve is pivoted upon the rod 20 and has a curved lower face 21 to reduce the impact upon the valve, and more easily divert the fluid through the pipe 3 when the parts are in the position of Figure 2. A recess 22 is provided in the rear of the head 6 to receive the valve 19, so that all portions thereof will be out of line of the upwardly directed fluid passing through the portion 18. The rod 20 carrying the valve is operated by means of the arm 23 on the end of such rod, which arm 23 is in turn operated by the connecting rod 8 which extends to a bracket 24 at the rear of the machine. The rear end of the rod 8 is screw threaded for the adjustment of the handle 25, and such handle 25 is adapted to take against a block 26, which is held spaced away from the bracket 24 by means of the spring 27. When the valve 19 is moved partly toward the position of Figure 2, and the impact of the oil carries it violently to its final position, the handle 25 striking against the spring-supported member 26 secures a spring seating of the valve, and injury to the parts is avoided. In order to take a certain amount of strain off the holding catches 17, it is desirable to add the weight of the apparatus to assist in anchoring the device against vertical movement, and in order to accomplish this result the wheels 4 are mounted for vertical adjustment as are also the wheels 5, so that after the device is positioned over the well casing the wheels 4 may be raised from the ground, and the wheels 5 lowered, thereby throwing the weight of the device to a large extent upon the point of engagement between the head 6 and the well casing 1. In order to secure the vertical adjustment of the wheels 4, they are mounted upon the U shaped axle 11 (Figure 3), and this axle is made rotatable

by means of the segmental worm-wheel 28 keyed to the axle 11 as indicated in Figures 3 and 7, which worm-wheel is operated by the worm-gear 29 carried by the bearing 30 also mounted upon the axle 11 in the manner shown in Figure 2. The worm-gear is rotated by means of its shaft 32 which extends to the rear of the apparatus and carries the hand-wheel 33, the portion of the shaft adjacent the hand-wheel being loosely supported by the bracket 31 secured to the pipe 2. It will be seen that by rotating the worm-wheel 28 about the axis of the wheels the horizontal portion of the axis 11 carrying the pipe may be raised and lowered. In order to make the rear wheels 5 adjustable with respect to the pipe 2, a bracket 34 is secured to the pipe 2, and it is made adjustable with respect to the frame-work 35 carried by the wheels 5 by means of the screw 36 swiveled at its lower end in such frame 35 and working through a nut 37 upon the yoke 34.

In operation the machine having the parts in the position shown is moved to a position with the head 6 over the well casing 1, at which time the hand-wheel 33 is operated to move the U shaped axle 11 carrying the pipe off center, and permit the apparatus to fall, so that the portion 16 (Fig. 2) engages the top of the pipe casing, and the spring-catches 17 clamp over the flange 18 of the well casing and hold the device firmly anchored to such casing. During this operation, the valve 19 is held in its rearward position in the recess 22, and the cap 10, (Fig. 1), is opened so that the fluid from the well passes unconfined upward through the pipe 7, while the parts are being positioned. After the parts are positioned, the rod 8 is pushed forward so that the valve 19 assumes the position shown in Figure 2, the impact of the fluid tending to carry the valve to its seated position after it passes into the stream of fluid, and the spring 27 permitting a seating of the valve without undue shock to the parts. The supply of oil and gas to the upper strata of air being cut off and the oil confined in the lateral pipe 2, the fire is extinguished because of lack of air, or if necessary steam or other extinguishing vapor may be supplied to the pipes 7 and 2 by means of the pipe 9, shown in Figure 1. After the fire has been extinguished the valve 19 may be returned to its original position in the recess 22 allowing the fluid to escape upward through the pipe 7 again, and the apparatus detached from the well casing and removed. To assist in the extinguishment of the fire in the pipe 7, the cap 10 may be closed by means of the chain 38 preliminary to the applying of the steam through the pipe 9. The adjustment of the wheels 5 provides for the elevation of such wheels when the apparatus

is being wheeled about on the wheels 4, and the subsequent lowering of such wheels preliminary to the lowering of the apparatus about the axle 11. It will be understood, 5 that when the device is lowered over the well casing the principal weight is borne by the rear wheels 5 and the well casing 1, so that the weight of the device, which is considerable, assists materially in holding the apparatus 10 against vertical movement when the valve 19 is moved to the position of Figure 2.

An alternative method of clamping the device to the well casing 1 is shown in Figures 5 and 6. As here shown the truss-member 39 15 is secured to the bottom of the pipe 2 and projects to a position with its other end adjacent to the well casing which latter end is provided with a plate 40, and is supported against vertical movement by means of the 20 connecting rods 41 provided with the adjusting turn-buckle 42. The plate carries pivoted to its under-side the tongs 43, adapted to clasp the pipe beneath the flange 18 and securely hold the apparatus against vertical 25 movement. The tongs are operated by means of a pair of toggle levers 44 provided with an operating rod 45 extending to the rear of the machine. The spring catches 17 30 may be used with apparatus of Figure 5 if desired.

Having thus described my invention and illustrated its use, what I claim as new and desire to secure by Letters Patent is the following:—

35 1. An extinguisher for wells comprising a movably mounted lateral pipe line adapted to make connection with the top of a well tube, means for supporting the pipe in position and means whereby the fluid from the 40 well is allowed to escape freely upward through the apparatus while the apparatus is being positioned.

2. An extinguisher for wells comprising a movably mounted lateral pipe line adapted 45 to make connections with the top of a well tube, means for securing the end of the pipe to the well casing and means whereby the fluid from the well is allowed to escape freely upward through the apparatus until the securing means is adjusted and then directing 50 such fluid through the lateral pipe line.

3. An extinguisher for wells comprising a movably mounted lateral pipe line adapted 55 to make connections with the top of a well tube, spring catches for securing the end of the pipe to the well casing, and means whereby the fluid from the well is allowed to escape freely upward through the apparatus until the catches engage the well casing and then directing such fluid through the lateral pipe line.

4. An extinguisher for wells comprising a 60 movably mounted lateral pipe line having an upwardly directed outlet adjacent its end and means for directing fluid either through

such outlet or through the pipe, and means for anchoring the end of the pipe over the well casing.

5. An extinguisher for wells comprising a laterally directed pipe line having a downwardly extending end, a truck on which the pipe line is carried in such manner that the downwardly extending end may be moved vertically, catches on the downwardly extending end for engaging the top of a well 75 casing, a vertical outlet pipe extending upwardly from the downwardly directed end and means whereby the fluid entering the downwardly extending end may be directed either upward through the outlet pipe or 80 laterally through the pipe line.

6. An extinguisher for wells comprising a laterally directed pipe line having a downwardly extending end, a truck on which the pipe line is carried in such manner that the 85 downwardly extending end may be moved vertically, catches on the downwardly extending end for engaging the top of a well casing, a vertical outlet pipe extending upwardly from the downwardly directed end 90 and means whereby the fluid entering the downwardly extending end may be directed either upward through the outlet pipe or laterally through the pipe line, and a cap and extinguishing means for the outlet pipe. 95

7. A movable extinguisher for wells comprising in combination, a head for fitting the well casing having an upwardly directed outlet, a laterally extending pipe connected to the head, and a valve for sending the 100 flow from the well either through the said pipe or permitting it to escape through the outlet.

8. A movable extinguisher for wells comprising in combination, a head for fitting the 105 well casing having an upwardly directed outlet, a laterally extending pipe connected to the head, a valve for sending the flow from the well either through the said pipe or permitting it to escape through the outlet, and 110 connections for applying an extinguishing fluid to the interior of the pipe.

9. A movable extinguisher for wells comprising in combination, a head for fitting the well casing having an upwardly directed outlet, a laterally extending pipe connected to the head, a valve for sending the flow from the well either through the said pipe or permitting it to escape through the outlet and 115 connections for applying an extinguishing 120 fluid to the outlet portion of the head.

10. A movable extinguisher for wells comprising in combination, a head for fitting the well casing having an upwardly directed outlet, a laterally extending pipe connected to 125 the head, a valve for sending the flow from the well either through the said pipe or permitting it to escape through the outlet, and an adjustable supporting means for the apparatus whereby the apparatus may be 130

lowered so that its weight rests partially upon the well casing.

11. An extinguisher for wells comprising a movably mounted lateral pipe line having an upwardly directed outlet adjacent its end and means for directing fluid either through such outlet or through the pipe.

In testimony whereof I have hereunto signed my name in the presence of the two subscribed witnesses.

MAHLON E. LAYNE.
